[57] CLAIM

The ornamental design for a tire, as shown and described.

DESCRIPTION

FIG. 1 is a side elevational view of a tire showing my new design;

FIG. 2 is an end elevational view thereof; and

FIG. 3 is a perspective view thereof it being understood that the tread pattern is repeated uniformly throughout the circumference of the tire, the opposite side being substantially the same as that shown.

FIG. 1

FIG. 2

FIG. 3
